UNITED STATES PATENT OFFICE.

JOHN J. WRIGHT, OF SALAMANCA, NEW YORK, ASSIGNOR OF ONE-HALF TO
ARTHUR D. BEDELL, OF SAME PLACE.

DESIGN FOR A TOWEL-RACK.

SPECIFICATION forming part of Design No. 32,281, dated February 27, 1900.

Application filed January 28, 1900. Serial No. 2,548. Term of patent 3½ years.

To all whom it may concern:

Be it known that I, JOHN J. WRIGHT, a citizen of the United States, residing at Salamanca, in the county of Cattaraugus and State 5 of New York, have invented and produced a new and useful Design for Towel-Racks, of which the following is a specification.

My invention relates to new and original designs in towel-racks.

Figure 1 is a front elevation of my design. Fig. 2 is a side elevation of the same. Fig. 3 is a perspective.

My new design is adapted to be constructed of a single piece of material; and it consists of a 5 loop 1 and two outwardly, upwardly, and backwardly curved symmetrical members 2, enclosing a pear-shaped space, the substantially parallel parts 3, the twisted portion 4, and the straight portion 5, bent at right angles to portions 3 and terminating with a loop 6, bent at right angles to part 5.

My design is so proportioned that a line joining the loops 1 and 6 would be approximately parallel to the parts 3.

The essential or material feature of my design is the principal members consisting of the parallel portions 3 and the curved portions 2. 25

Having thus described my new design, what I claim, and wish to secure by Letters Patent, 30 is—

The design for a towel-rack, substantially as described and shown.

In testimony whereof I have hereunto set my hand in presence of two subscribing witnesses. 35

JOHN J. WRIGHT.
